SELF-LEVELING DISPENSER

Arthur P. Simpson, River Edge, N.J., assignor to American Machine & Foundry Company, a corporation of New Jersey

Filed Apr. 2, 1956, Ser. No. 575,633

3 Claims. (Cl. 211—49)

This invention relates to a storing and dispensing apparatus of the self-leveling type.

In self-leveling dispensers, particularly those designed for carrying loads in excess of 300 pounds, it has been found that there is sometimes a tendency for the dispenser to be sluggish in rising from its fully loaded position. This is particularly true in a cantilever type self-leveling storing and dispensing apparatus. Part of the sluggishness has been due to the increase in friction when the dispenser is fully loaded, and part may be due to the canting effect that results from the use of a cantilever-type, self-leveling dispenser.

Heretofore, attempts have been made to provide for this problem by incorporating auxiliary energy-adding devices such as hydraulic or mechanical means to overcome the sluggishness referred to, while in other cases staggered linkages have been employed.

It is an object of the present invention to overcome this sluggishness by providing a supplemental compression spring directly underneath the platform that supports the load so that an additional counterbalancing force is exerted directly on the load. This has the advantage that not only is a high capacity tension spring lifting force being exerted on the carrier but also a compression spring force directly at the point where it is most needed when the heaviest load is being supported, to thereby overcome the frictional and canting forces referred to.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Figure 1 is a side elevation, partly in section, of a self-leveling, storing and dispensing apparatus incorporating the present invention.

Figure 2 is an end elevation taken on line 2—2 of Figure 1.

Figure 3 is a cross-sectional side elevation of a modified form of my invention.

Figure 4 is a cross-sectional end elevation taken on line 4—4 of Figure 3.

Figure 5 is a partial end section taken on line 5—5 of Figure 3.

With reference to the drawings the self-leveling dispenser shown in Figure 1 consists of a base 10 supported on a pair of casters 12 and a pair of swivel casters 14 mounted on the ends of the base 10. An upright framework or housing 16 extends upwardly from one side of the base 10. A cantilever carrier, platform or carriage 18 is mounted for up and down travel on the upright 16. The carriage 18 has a pair of arms 20 which extend through suitable slots 22 formed in the face of the upright 16.

2

A pair of downwardly extending legs 24 having rollers 26 thereon ride on the front surface of the upright 16 while a pair of upwardly extending legs 28, having rollers 30 mounted thereon track on the inside of the upright 16. 5 Another pair of rollers 32 is provided for tracking against the inside 34 of the upright 16 to prevent the carrier 18 from moving sidewise while it travels up and down.

It will thus be noted that the cantilever platform is maintained level as it rides up and down on the vertical upright 16 in a manner similar to that shown in U.S. Patent 2,662,802, granted to William J. Gibbs on December 15, 1953.

A sprocket chain 36 is connected at one end to the cantilever platform 18 and is adjustably connected at the other end to a bracket 38 extending from the upper end of the upright 16 by means of a conventional bolt and nut assembly 40. Elongated flexible members such as sprocket chains 36 are trained over a pair of sprockets 42 supported at the upper end of the upright 16, and are trained downwardly to form a loop 44 for supporting a saddle shaft 46 having a pair of freely rotatable sprockets 48 mounted thereon in a manner similar to the aforementioned Patent 2,662,802.

It will be appreciated that while I have shown a dispenser employing a 2 to 1 ratio, any other ratio such as 1 to 1 or 3 to 1 could also be employed to provide a counterbalancing arrangement.

A plurality of calibrated tension springs 50 connected in between the base 10 and the saddle shaft 46 are provided for imparting a calibrated counterbalancing force to the cantilever platform 18 which will vary proportionately to the distance the cantilevered platform 18 is moved so as to maintain the top of the material supported on said platform at a substantially constant level by lowering or raising the platform 18 a proportional distance correlated with the weight of each increment or decrement of material added to or removed from that stored on the platform 18.

From this description it will be apparent that when material such as tote boxes 52 stacked thereon, the additional downward force exerted by gravity will cause the calibrated counterbalancing springs 50 to stretch a proportionate amount. As indicated the springs 50 are calibrated so as to exert a force sufficient to maintain the top of the top box 52 at a substantially constant level with respect to the upper end of the upright 16.

As additional weight is added to the weight supported on the cantilevered platform 18, the platform 18 descends until it comes into contact with the cover plate 54 secured to the top of compression springs 56. The lower ends of the calibrated compression springs 56 are connected to the lower plate 58. The lower plate 58 is connected by suitable means such as welding to the base 10.

As the platform 18 continues to have more material stacked thereon, it will continue its descent compressing the compression springs 56 while simultaneously stretching the tension springs 50.

When all the material has been completely stored on platform 18 and the unloading has commenced, as material is removed from the top of the stack there will be upward pressure exerted on the platform 18 by the tension springs 50 and the compression springs 56. The compression springs 56 acting directly against the under side of the platform 18 not only tend to diminish the frictional forces being exerted on the sprocket bearings and the links of the sprocket chain, but also on the rollers 26 and 30. Also the upward force exerted by springs 56 tends to correct the torque exerted by the cantilever platform 18 on the rollers traveling on the

upright 16 by exerting a force in the opposite direction. While I have shown the compression springs as being fixed at their lower ends to the base 10, it will be appreciated that the compression springs could have been mounted on the under side of the carrier 18. In this case they would engage with the base as the carrier is lowered. The important factor is that compression springs be interposed between the carrier and the base so that they will be compressed when the carrier is in the lowermost position.

In the modified form of my invention I have shown how the supplemental compression springs may be employed with respect to a carrier or platform that is supported at four corners, instead of just on one side, in a manner similar to that shown in U.S. Patent 2,649,992, granted to Christopher Bockius on August 25, 1953. In this embodiment of the invention, the self-leveling dispenser consists of a housing 60 which is supported on stationary casters 62 and swivel casters 64.

The material supporting carrier or platform 66 is supported by a pair of suitable brackets 67 which are attached to spaced sprocket chains 68 which travel over a pair of pulleys 70 and are adjustably connected at the opposite end by means of an adjusting nut 72 and a bracket 74 through which the bolts 76 extend. The other side of the platform 66 is connected to brackets 71 which are connected to the ends of a pair of spaced sprocket chains 78 which pass over sprockets 80 and a pair of sprockets 73 mounted on the shaft 69 in a manner similar to that shown in U.S. Patent 2,649,992.

The ends of these chains 78 are similarly connected to suitable adjusting anchors in the same manner as sprocket chains 68. A saddle shaft 82 on which two pair of sprockets 79 and 84 are freely mounted is supported in the loops 86 and 87 formed by the sprocket chains 68 and 78.

When material is placed on top of the material supporting platform 66 the platform descends drawing the sprocket chains 68 and 78 over their respective sprockets. This action causes the loop 86 to shorten, which, in turn, causes the calibrated tension spring 88 to be stretched a distance which will maintain the top of the material at a substantially constant level.

As the loading process is continued, the platform 66 ultimately comes into contact with the plate 90 connected to the upper end of compression springs 92. The plate 90 is secured to the top of springs 92 by suitable means such as clamps or welding and the springs are supported at their lower end on a lower plate 94 which is fixed to the bottom of housing 60.

As the platform 66 continues its descent, it causes the compression springs 92 to be compressed until it reaches its lowermost limit of travel.

When the platform 66 has reached its lowermost limit of travel, the greatest amount of friction will then be exerted upon the sprockets 70 and 80, and upon the links of the sprocket chain. Due to the large amount of friction generated in these moving parts as well as the inertia of the platform itself, there ordinarily would be a tendency for the platform 66 to stick or be sluggish which, of course, is undesirable because the material then would not be maintained at a constant level. However, owing to the present compression springs 92, this tendency of the carrier to hesitate at this point of the unloading process is overcome by the compression springs 92 possessing sufficient load characteristics and applying a direct lifting force to the bottom of the platform 66 to overcome the inertia resistance to rising. As a consequence the platform maintains the top of the material at a substantially constant level, even though the weights supported are exceedingly heavy.

As previously indicated the compression springs 92 could be mounted on either the base of the dispenser or can be secured to the underside of the platform or carrier. The important factor is that they be positioned to be

4
compressed between the carrier and the base when the carrier is in its lowermost position so that they can use this stored energy to lift the carrier when the unloading operation commences.

The invention herein above described may be varied in construction within the scope of the claims, for the particular device selected to illustrate the invention is but one of many possible embodiments of the same. The invention, therefore, is not to be restricted to the precise details of the structure shown and described.

What is claimed is:

1. A self-leveling, storing and dispensing apparatus comprising a base, an upright framework extending upwardly from said base, a carrier movable up and down relative to said upright framework above said base, means for maintaining said carrier horizontal when it travels up and down, calibrated yieldable tension spring means anchored against movement at one end and connected at a portion remote from said anchored end to said carrier, said tension spring means being of a tension which will exert a counterbalancing force which will be proportional to the distance said carrier moves so as to maintain the top of the material supported thereon at a constant level by raising or lowering said carrier a distance corresponding to the weight of each decrement or increment of material removed from or added to said carrier, a compression spring unit positioned in the path of the descending carrier and secured at its lower end to said base and having its upper end free and located beneath said carrier at a substantial distance below the carrier's upper position, said springs possessing sufficient load characteristics to engage said carrier supplementing the lifting effect of said tension spring means only at the lower portion of the carrier's movement to overcome the initial inertia resistance to rising.

2. A self-leveling, storing and dispensing apparatus comprising a base, an upright framework extending upwardly from said base, a cantilever platform movable up and down on said upright framework above said base, means for maintaining said cantilever platform horizontal when it travels up and down, calibrated tension spring means anchored against movement at one end and connected at the other end to said cantilever platform, said tension spring means being of a tension which will exert a counterbalancing force which will be proportional to the distance said cantilever platform moves so as to maintain the top of the material supported thereon at a constant level by raising or lowering said cantilever platform a distance corresponding to the weight of each decrement or increment of material removed from or added to said cantilever platform, a compression spring unit positioned in the path of the descending cantilever platform and secured at its lower end to said base and having its upper end free and located beneath said cantilever platform at a substantial distance below the cantilever platform's upper position, said spring possessing sufficient load characteristics to engage said cantilever platform supplementing the lifting effect of said calibrated tension spring means only at the lower portion of the cantilever platform's movement to overcome the initial inertia resistance to rising.

3. A self-leveling, storing and dispensing apparatus comprising a base, a four sided upright framework extending upwardly from said base, a carrier movable up and down inside of said framework, a plurality of calibrated tension spring means anchored against movement at one end and connected at the other end to said carrier, said tension spring means being of a tension which exert a counterbalancing force which will be proportional to the distance said carrier moves so as to maintain the top of the material supported thereon at a constant level by raising or lowering said carrier a distance corresponding to the weight of each decrement or increment of material removed from or added to said carrier, a compression spring unit positioned in the path of the descend-

ing carrier and secured at its lower end to said base and having its upper end free and located beneath said carrier at a substantial distance below the carrier's upper position, said spring possessing sufficient load characteristics to engage said carrier supplementing the lifting effect of said calibrated tension spring means only at the lower portion of the carrier's movement to overcome the initial inertia resistance to rising.
